UNITED STATES PATENT OFFICE.

JOSIAH O. BURNS, OF LOS ANGELES, CALIFORNIA, ASSIGNOR TO GERMAIN SEED AND PLANT COMPANY, OF LOS ANGELES, CALIFORNIA, A CORPORATION OF CALIFORNIA.

DISPLAY-RACK.

1,274,509.

Specification of Letters Patent.

Patented Aug. 6, 1918.

Application filed June 12, 1917. Serial No. 174,214.

To all whom it may concern:

Be it known that I, JOSIAH O. BURNS, a citizen of the United States, residing at Los Angeles, in the county of Los Angeles and State of California, have invented a new and useful Display-Rack, of which the following is a specification.

This invention relates to devices of the character designed to hold packages or other objects intended for sale. One use to which this device is well adapted is the holding of packets of seed or the like.

An object of the invention is to provide a device of this character which is comparatively inexpensive to construct and durable and neat in appearance.

Another object is to make provision for holding the packages securely and yet in such manner that they can be readily withdrawn from the device when desired.

Another object is to so construct the device that the packages will be supported above the floor of the establishment where the goods are being exhibited.

Another object is to effect the locking into open position of the movable sections by means of the support.

Another object is to produce a device of this character comprising any desired number of duplicate units, each unit being of unitary construction.

Other objects and advantages will appear in the subjoined detail description.

The accompanying drawings illustrate the invention.

Figure 1 is a front elevation of the rack in open position.

Fig. 2 is a rear elevation of the rack shown in Fig. 1.

Fig. 3 is an enlarged sectional elevation on line indicated by x^3-x^3 , Fig. 1, a portion of the standard being broken away to contract the view.

Fig. 4 is an enlarged sectional elevation on line indicated by x^4-x^4 , Fig. 1.

Fig. 5 is a front elevation of the rack in Fig. 1 with the foldable swinging sections in closed or folded position.

Fig. 6 is a view of one of the back-forming and partition-forming strips or blanks of the stationary section.

Fig. 7 is a view of one of the back-forming and partition-forming blanks of one of the movable sections.

Fig. 8 is a plan section on the irregular line indicated by x^8-x^8 , Fig. 1.

Fig. 9 is a plan view of one of the transverse members forming the horizontal partitions.

Fig. 10 is a perspective view looking at the back of the rack with the foldable sections locked in open position.

Fig. 11 is an enlarged sectional detail on line indicated by $x^{11}-x^{11}$, Fig. 8.

The rack in the instance shown comprises a stationary section 1 and two foldable sections 2 fastened by hinges 3 to the stationary section so that they can be extended as in Fig. 1 or folded into closed position as in Fig. 5. It is understood that the number of sections may be varied at will and that the size thereof may be in accordance with the desires of the constructor.

The backs of the sections 1, 2 are formed by vertical strips 4, 5 respectively, and the number of these strips may be greater or less according to the width of the sections desired. Bent from the strips 4, 5 at right angles thereto and at both side edges thereof are wings 6 terminating at their free ends in flanges 7 which are bent parallel to the strips and extend in front of said strips as clearly shown in Fig. 8. Adjacent wings 6 of adjacent strips are positioned back to back and the wings 6 are provided with one or more tongues 8 projecting through perforations 9 in horizontal transverse members 10, said tongues being bent beneath the partition members so as to securely connect the wings to said transverse members. Each perforation accommodates a tongue from each of two adjacent wings. The wings thus form vertical partitions.

The transverse members themselves are provided at their ends with tongues 11 which pass through perforations 12 in vertical side members 13 of the sections, said tongues 11 being bent over upon the outside of the side members so as to securely hold the transverse members and side members together. The lowermost transverse members 10 of the various sections 1, 2 form the bottom mem-

bers of the pocket-containing recess A, and the uppermost transverse members 10 of the different sections constitute top members of the recess A, and the other transverse members form horizontal partitions between vertical series of pockets 14, the pockets in each series being partly separated from one another by the wings 6.

At the top of each section 2 may be provided a space 15 for advertising purposes and also at the top of the section 1 may be provided a space 16 for the same purpose.

From the foregoing it is clear that the sections are each provided with a number of pockets capable of holding packages one behind the other, for instance, packets of seeds, and that because of the provision of the wings 6 and the fastening of the wings to the transverse members the sections, though employing a number of units, are comparatively rigid.

When the packets are in the pockets 14 the front ones are retained by the flanges 7 against the pressure of the packets behind. The packets may be pressed outward so as to be held in vertical position with the outermost ones against the flanges 7 by springs 17. These springs are inserted through perforations 18 in all of the transverse members excepting the lowermost ones and the inserted ends of the springs are bent over upon the transverse members and fastened in place by rivets 19 as clearly shown in Figs. 4 and 8.

The sections 1, 2 are provided at their rear faces with hooks 20 adapted to hook over an upper cross bar 21 which is fastened to standards 22 connected together near their lower ends by a lower cross bar 23. The standards 22 are furcated at their lower ends so as to form feet 24 capable of holding the standards and the sections mounted thereon in vertical position.

The hooks 20 are arranged in two series, one series being on the section 1 only and being near the upper portion of said section and the other series being partly on the section 1 and partly on the sections 2 nearer the lower ends of the sections. When the upper series of hooks engages the bar 21 the sections 2 are free to be swung into closed position, and when the lower series of hooks engages the bar 21 the folding sections 2 are held against closing and the three sections are raised higher on the standards than when the upper series of hooks engages said bar.

From the foregoing it will be clear that the sections can be readily stamped entirely from sheet metal and that the various parts thereof can very readily be assembled into proper relation with one another to complete the sections.

It is believed that the foregoing makes

clear the construction and operation of the 65 device.

Ordinarily when in use the section 2 will be swung into open position and the lower series of hooks 20 will be engaged with the bar 21 as in Fig. 10. When it is desired to close the device, the sections will be raised to release the hooks from the bar 21 and said sections will be lowered to bring the upper series of hooks into engagement with the bar 21 and the sections 2 will then be folded toward the section 1 so as to close all of the pockets in the sections 1 and 2, the open sides of the pockets of the sections 2 closing against the open sides of the pockets of the section 1.

The only difference between the section 1 and the sections 2 in construction is that the sections 2 are shallower, narrower and shorter than the section 1, but it is understood that all of the sections may be of any size desired according to the use to which the rack is to be put.

I claim:

1. A display rack comprising a stationary section, a movable section hinged to the stationary section, and a support detachably engageable with the stationary section alone so that the movable section can be swung into closed position and also detachably engageable with the stationary and movable sections to prevent closing of the movable section.

2. A display rack comprising a section having a back formed of vertically arranged strips, wings extending forward from both sides of each of the back strips and terminating in flanges parallel to the back and spaced therefrom, transverse members fastened to said wings, and side members fastened to the transverse members.

3. A display rack comprising a stationary section, a movable section hinged to each side of the stationary section, and a support shiftably engageable with the stationary section, said support in one position engaging the movable sections.

4. A display rack comprising strips, wings bent at an angle from said strips, transverse partition members having perforations, and tongues on the wings passing through the perforations and bent beneath said transverse members.

5. A display rack comprising strips, wings bent at an angle from said strips and terminating in flanges extending parallel to the strips, side members having perforations, transverse partition members having perforations and having tongues at their ends passing through the perforations in the side members and bent over on the outsides of the side members, and tongues on the wings passing through the perforations and bent beneath said transverse members.

6. A display rack comprising vertically extending strips each having a series of separate wings along its side edges to form the sides of pockets, and a partition member 5 extending transversely between each two adjacent wings of both series of all of the strips.

Signed at Los Angeles, California, this 31st day of May, 1917.

JOSIAH O. BURNS.
